(57) **CLAIM**

We claim the ornamental design for a bone chip collection basket, as shown and described.

DESCRIPTION

FIG. 1 is an environmental perspective view of the bone chip collection basket, from the top position;

FIG. 2 is a left side view thereof;

FIG. 3 is a front view thereof;

FIG. 4 is a right side view thereof;

FIG. 5 is a back view thereof;

FIG. 6 is a top view thereof;

FIG. 7 is a bottom view thereof;

FIG. 8 is a perspective view of the bone chip collection basket, from the top position;

FIG. 9 is a left side view thereof;

FIG. 10 is a front view thereof;

FIG. 11 is a right side view thereof;

FIG. 12 is a back view thereof;

FIG. 13 is a top view thereof; and,

FIG. 14 is a bottom view thereof.

The features shown in broken lines in various Figures are for illustrating reference or environmental structure.
